(57) **CLAIM**

The ornamental design for a paint brush with integrated grip pad, as shown and described.

DESCRIPTION

FIG. 1 is a top, front, left perspective view of a paint brush with integrated grip pad showing our new design;

FIG. 2 is a bottom, rear, left perspective view thereof;

FIG. 3 is an enlarged top, front, left perspective view thereof taken from section 3 in FIG. 1;

FIG. 4 is front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The uniform broken line showing in FIGS. 1-9 is for the purpose of illustrating portions of the paint brush with integrated grip pad and forms no part of the claimed design. The dot-dash broken line showing in FIGS. 1, 3 and 4 are for the purpose of illustrating a boundary line, and forms no part of the claimed design.

The dot-dot-dash broken line shown in FIGS. 1 and 3 are for the purpose of depicting enlarged view indicators, and form no part of the claimed design.

The stippling showing on the grip pad in FIGS. 1, 3 and 4 indicates a contrast in appearance.
